METHOD AND APPARATUS FOR SELECTING METAL CHECKS.

Application filed January 27, 1928 Serial No. 250,036.

This invention relates to the selection of checks having certain properties from other checks not possessing such properties, for example for the purpose of preventing operation 5 of vending machines, change delivering machines or other coin controlled or check controlled apparatus by any coins or checks other than those by which the same are intended to be operated.

10 The main object of the invention is to provide a novel method and apparatus for the above purpose.

A particular object of the invention is to provide for double selecting action dependent 15 upon the combined properties of electrical conductivity and resiliency, whereby checks having a certain electrical conductivity and a certain resiliency will be delivered separately from the checks differing therefrom either in 20 electrical conductivity or resiliency.

The invention consists both in the method and apparatus, the method consisting essentially in causing the check to be tested to pass into and through a zone of concentrated magnetic flux, whereby the velocity of the check 25 is modified in accordance with its electrical properties as hereinafter described, and subsequently causing checks delivered in a certain path as a result of the intensity of the 30 velocity-modifying action of said magnetic flux, to strike against impact means and rebound therefrom, and selectively delivering the checks so striking said impact means and undergoing a certain amount and direction of 35 rebound separately from checks failing to properly strike the impact means or failing to rebound in the proper manner after striking said impact means. The check is delivered through space, after passing through the zone 40 of magnetic flux, so as to cause it to travel in a free trajectory dependent upon the velocity at which the check leaves said zone. A certain kind of coin does not always travel exactly the same trajectory, due to variations in 45 surface condition, and, indeed, the same coin will experience slight changes in trajectory, if repeatedly inserted, probably due to slight variations in vibration as it passes down the chute. This variation in trajectories is taken 50 care of by making the impact surface of the impact member just wide enough to span the limits of variation. The width may be cut down to even less to secure a greater selectivity, since the only result is to return an

occasional coin to the customer. By performing the separation by means of an edge on a massive impact member, a high degree of accuracy is obtained. This we believe to be due to the fact that there is no wavering of the edge when it is struck by a check, such as 55 might occur where the separation is done by a thin partition. Such a wavering might cause a check having a trajectory very near the line of division to fall sometimes on one side and sometimes on the other. With our impact member the action is always the same 60 for a coin travelling the same trajectory. For this reason we are able to obtain an accurate selection between checks of such similar electrical conductivity and weight as silver and 65 copper, for example.

The apparatus of our invention comprises 70 essentially, means defining a passage for checks, means for creating a concentrated magnetic field across or through a certain 75 portion of said passage in such manner that the lines of force are cut by a check moving in said passage, suitable impact means disposed in the path of checks following a certain trajectory after leaving said passage, and 80 means for selectively delivering the checks after rebound from said impact means, in accordance with the trajectory thereof after such rebound.

The accompanying drawings illustrate 85 embodiments of the apparatus of our invention and referring thereto:

Fig. 1 is a vertical section of one form of such apparatus.

Fig. 2 is a section on line 2—2 in Fig. 1.

Fig. 3 is a section on line 3—3 in Fig. 2.

Fig. 4 is a section on line 4—4 in Fig. 1.

Fig. 5 is a vertical section of another modification of the apparatus.

In the apparatus shown in Figs. 1 to 4 inclusive, a chute 1 is provided having a downwardly inclined check conducting passage 2 and an opening 3 for insertion of a metal check in the upper end of said passage. Means are provided for creating a strong 95 magnetic field across any suitable portion of the passage 2, such means comprising for example one or more magnets disposed in position to concentrate their magnetic flux across said passage. In the particular form shown such means comprise two horseshoe magnets 4 and 5 disposed respectively above 100 and below the chute 1. Said magnets may 105

consist of permanent magnets as shown, although it will be understood, of course, that electromagnetic means may be used to accomplish the same result if desired. The like poles of said magnets are secured in position in contact with common pole pieces 6 and 7, the two north poles being, for example, secured in contact with pole piece 6 and the two south poles in contact with the pole piece 10 7. Said pole pieces are preferably provided with means for concentrating the magnetic flux therebetween across a limited portion or zone of chute 2, such means comprising for example L-shaped members 8 and 9 formed 15 on or secured to the respective pole pieces, the inner ends of said members projecting through the side walls of chute 1 as shown, so as to leave a gap therebetween just sufficient to permit passage of the check and concentrate said flux through the smallest possible 20 portion of the check and thus produce the maximum effect thereon.

Chute 1 opens at its lower end and beyond the opposing members 8 and 9 into an enlarged chamber or housing 12 providing a passage 13 between the side plates 14 thereof, said passage being only slightly greater in width than the thickness of the checks designed to pass therethrough but having a sufficient extension in the plane of said check to permit any check to fall freely therethrough in different paths under the influence of gravity, depending upon the weight of the check and the velocity with which it leaves the passage 2. At a suitable point in chamber 12 is mounted an anvil or impact member 16 which extends from one side plate 14 to the other, but whose dimension in a direction substantially perpendicular to the 30 trajectory of the check is considerably less than that of the chamber 12 so as to provide a space 17 in front of said impact member and a space 18 beyond the same of sufficient size to permit passage of checks therethrough. Said impact member may be of steel or other suitable metal or of bakelite or any other suitable material and is of sufficient size and weight to cause a check falling thereon to rebound in the desired manner. The impact member is placed as shown, below and somewhat beyond the lower end of chute 1, so that a check leaving said chute at exactly a predetermined velocity will strike said impact member squarely upon its upper or impact face 19 and rebound in the desired manner provided such check possesses the desired property of resiliency.

Beyond and somewhat above the impact member 16 is mounted an adjustable deflecting member 21 which may be set in any desired position between the side walls 14, said deflecting member comprising, for example, a short metal sleeve or section of tubing held in position by means of screw 22 extending 60 through slots 23 in said side walls and se-

cured by 24. By moving said deflecting member up or down in the slots 23 the same may be set in such position that a check striking the upper face of impact member 16 squarely and possessing the proper resiliency will rebound over said deflecting member, while any check of less resiliency will strike said deflecting member and be thrown back and fall through one of the passages 17 or 18. At the other side of the deflecting member 21 is provided 70 a downwardly extending check receiving chute 26 into which any check rebounding over said deflecting member is permitted to fall. The end of chamber 12 is closed as indicated at 27 and is preferably rounded as 75 shown so as to catch all checks passing over the deflecting member and guide the same into the chute 26. Chamber 12 may communicate at its lower end with a chute 28 into which any checks passing through the 80 spaces 17 or 18 are delivered.

If desired, an additional deflecting member may be provided as indicated in dotted lines at 21' for intercepting checks having greater resiliency than that desired, said deflecting member being, for example, similar to member 21 and being mounted in the upper portion of the same slots 23.

The operation of the above described form of apparatus is as follows: A coin or check inserted through opening 3 into the upper end of passage 2 will roll downwardly in said passage and through the zone of concentrated magnetic flux between the opposing pole members 8 and 9. The motion of such check through the magnetic field will cause induced electric currents commonly known as eddy currents to be set up therein by electromagnetic induction and will at the same time cause a retarding force to be exerted upon the check, the strength of such force, for a given strength of magnetic field, depending primarily upon the electrical conductivity of the check. The strength of the retarding force thus exerted upon the check will influence the velocity thereof and thus determine the velocity at which the check is discharged from the zone of magnetic flux and from the lower end of passage 2. The greater the electrical conductivity of the substance of which the check is composed, the greater will be the retarding force and hence the less the velocity of discharge.

The effective or apparent electrical conductivity of the check, upon which the retardation or modification of the motion of the check depends, depends not only upon the actual conductivity of the substance of which the check is composed, but also upon the shape or configuration thereof. For example, if the check be provided with perforations, its apparent or effective conductivity will thus be reduced. The term "electrical conductivity" as used herein is understood to mean the effective conductivity of the checks, that is, the

relative readiness with which eddy currents are induced therein upon passage through the magnetic field.

It should be pointed out that the method and apparatus of this invention are intended particularly for operation upon checks composed of non-magnetic or weakly magnetic substances, that is to say, upon substances which are not strongly paramagnetic, and are therefore not attracted upon being placed within a magnetic field, the action upon which the invention is based being dependent entirely upon the eddy currents and the resultant retarding force produced upon motion of the check through the magnetic field. The invention is, for example, adapted for handling checks composed of silver, gold, copper, lead, tin, zinc, antimony, or alloys thereof but it is not intended for the handling of checks made of iron, nickel or the like, which would be so strongly attracted as to be stopped by one or the other of the pole pieces.

Magnets 4 and 5, or other magnetic means which may be employed, are of sufficient strength, and impact member 16 is so placed with respect to the lower end of passage 2 that a check having a certain desired electrical conductivity and hence undergoing a certain retardation in its passage through the magnetic flux will leave such passage at just sufficient velocity to cause it to fall in substantially the path or trajectory indicated by the arrows at A in Fig. 1. Such a check will, therefore, strike the impact member in a certain pre-determined position and at a certain velocity and angle, so as to cause it to rebound properly provided it possesses also the proper resilience. Any check of like weight having a greater electrical conductivity will undergo greater retardation and be discharged at a lower velocity and hence fall in some such path as indicated at B while a check of less electrical conductivity will leave the passage at a greater velocity and fall in some such path as indicated at C. Checks following other than the proper path A may fall entirely clear of the impact member 16 as indicated by the paths B and C and hence be discharged through chute 28, or they may strike the impact face 19, but not squarely in the proper position thereon nor at the proper angle and velocity, and hence fail to rebound over the deflecting member 21 or between said deflecting member and the upper deflecting member 21', even though they may possess the proper resilience. Checks failing to rebound between said deflecting members because of improper impact on the impact member 16 will be thrown back into chamber 12 and hence pass downwardly at one side or the other of the impact member and through the same chute 28.

The apparatus will also reject any check which is not round, as such check will be caused to slide down the chute 1 instead of

rolling and due to the resulting greater frictional resistance its velocity at the time of leaving said chute will not be great enough to cause it to strike impact member 16 or at least to strike it in such manner as to rebound clear of the deflecting means 21 and 21'.

Furthermore, even though the check is round and possesses the proper electrical conductivity and therefore strikes the impact member 16 squarely on the impact face 19 thereof, it will still be rejected unless it also possesses a certain desired resiliency. If the check so striking the impact member has exactly the desired resiliency it will rebound in the path indicated at A' and hence pass between deflecting member 21 and 21' and pass downwardly through chute 26. If, however, it possess less resiliency it will fail to rebound sufficiently and will, therefore, strike deflecting member 21 and be drawn back and discharged through chute 28. In a similar manner a check having a greater resiliency than that desired will rebound to too great an extent and will strike deflecting member 21' with the same result.

A modification of the apparatus is shown in Fig. 5, in which the chute 1 provided with check conducting passage 2, and the means for creating magnetic flux across said passage may be substantially the same as before, but in which the impact member 16' is placed in a position more nearly in line with the direction of said passage instead of below the same so that a check leaving the passage 2 at relatively high velocity will be projected as indicated by the arrows E and strike the lateral impact face 19', so as to be deflected in some such path as that indicated as F and fall into the chute 31. The plane of the impact face is in this case such as to cause the check to rebound backward instead of forward, that is, to undergo a reversal in the horizontal component of its direction of travel. Deflecting members 32 and 32' may be provided which may be similar to the members 21 and 21' above described and may be mounted in similar manner in slots 33. A second delivery chute 34 may be provided in position to receive any check which leaves the passage 2 with a velocity insufficient to cause it to strike the impact face 19', for example a check travelling in the path indicated at G, as well as any check striking said impact face but rebounding therefrom in a path such as indicated at H, due to insufficient resiliency.

This form of apparatus is particularly adapted for the selection of checks of relatively low electrical conductivity, but relatively high resiliency, as checks of this character will be relatively slightly affected by passage through the magnetic field and will hence leave the passage 2 at high velocity, and will also rebound a maximum distance from the impact member 16'. The principles upon which the selection is based are, how-

ever, the same as in the form of apparatus first described.

We claim:

1. The method of selecting checks which comprises causing the check to pass through a zone of concentrated magnetic flux whereby the velocity of said check is diminished in accordance with the induced currents set up therein, permitting the check to move in a free trajectory after leaving said zone of magnetic flux, causing any check moving in a certain trajectory to strike against impact means and to rebound therefrom in accordance with the resiliency thereof, and delivering any check striking said impact means and rebounding therefrom in a certain manner separately from all checks failing to strike said impact means and all checks striking said impact means and failing to rebound therefrom in said certain manner.

2. An apparatus for selecting checks comprising means creating a zone of magnetic flux, means for delivering checks to said zone of magnetic flux so as to cause said checks to cut the lines of force of said flux, means for conducting checks from said zone in such a manner that they are free to move under the combined influence of their velocities and gravity, impact means positioned so as to be struck by checks travelling a certain trajectory, means adapted to receive checks rebounding from said impact means in a certain path and means adapted to prevent entrance of checks rebounding in any other path into said check receiving means.

3. The method of selecting checks which comprises causing the checks to pass through a zone of concentrated magnetic flux so as to cause the velocity thereof to be diminished in accordance with the induced currents set up therein, subsequently discharging the checks, in other than a vertical direction, so that they will move in free trajectories determined by the resulting velocities thereof, causing checks moving in a certain trajectory to strike and rebound from impact means, and selectively delivering the checks in accordance with the path followed thereby after such rebound, such path being determined by the combined effect of said resulting velocity of the check and its resiliency.

4. The method of selecting checks which comprises first subjecting the check to a selective action dependent upon the retardation thereof when passed through a zone of magnetic flux, subsequently discharging the check in a direction other than vertical, so that it will move in a free trajectory determined by its resulting velocity, and subjecting it while so moving to a selective action dependent upon the combined effect of the first-named selective action and of the resiliency of the check.

5. The method of selecting checks which comprises first passing the check through a

zone of magnetic flux to modify the velocity thereof in accordance with the electric induction therein, subsequently discharging the check in a direction other than vertical, and then subjecting the check, while moving in a free trajectory determined by its modified velocity, to a selective action dependent on the combined effect of the velocity of the check and the resiliency thereof.

6. The method of selecting checks which comprises passing the check through a zone of concentrated magnetic flux so as to modify the velocity thereof in accordance with the induced currents set up therein, causing the check upon leaving said zone to move in a free trajectory determined by its modified velocity, causing any check moving in a certain trajectory to strike upon impact means and to rebound therefrom, and selectively separating checks striking said impact means and rebounding therefrom in a certain path from checks failing to strike said impact means and from checks striking said impact means but failing to rebound in said certain path.

7. An apparatus for selecting checks comprising impact means, means creating a zone of magnetic flux, means defining a check conducting passage extending through said zone of magnetic flux and adapted to discharge a check in a direction other than vertical, whereby a check delivered from said passage at a certain velocity will thereupon fall in a free trajectory in such manner as to strike said impact means at a certain velocity and in a certain position, said impact means being adapted to cause a check striking the same to rebound in a path dependent upon the position and velocity of impact and upon the resiliency of the check, means defining a check receiving passage, and deflecting means in position to permit a check rebounding from said impact means in a certain path to enter said check receiving passage and to prevent checks rebounding in any other path from entering said passage.

8. An apparatus for selecting checks comprising a chute provided with a downwardly inclined check conducting passage, magnet means creating a zone of magnetic flux across a portion of said chute, housing means communicating with the lower end of said chute and adapted to permit a check upon leaving said chute to move in a free trajectory under the combined effect of its own momentum and the force of gravity, an impact member mounted within said housing means and having an impact face so positioned that a check following a certain trajectory through said housing means will strike said impact face and rebound therefrom in a manner dependent upon the position, direction and velocity of impact and upon the resiliency of the check, means defining a check receiving passage, deflecting means positioned within said housing means between said impact member and

said check receiving passage and adapted to permit a check rebounding in a certain manner from said impact member to pass said deflecting means and enter said check receiving passage but to deflect checks rebounding in any other manner and prevent the same from entering said check receiving passage, and means separate from said check receiving passage for receiving and conducting away checks failing to strike said impact member and checks deflected by said deflecting means.

9. A check selecting apparatus comprising means creating a zone of magnetic flux, a check conducting chute extending through said zone of magnetic flux, impact means arranged beyond the end of said chute, said magnetic flux being adapted to retard checks passing therethrough differentially in accordance with their composition, said chute being adapted to discharge checks in a direction other than vertical, whereby they will travel along trajectories determined by their momentum and gravity, said impact means having an edge located on the line of division between the trajectories of different kinds of checks, means defining a check receiving passage, and deflecting means adapted to exclude checks rebounding from said impact means

from said check receiving passage, except those traversing a certain path. 30

10. A check selecting apparatus comprising means creating a zone of magnetic flux a check conducting chute extending through said zone of magnetic flux, impact means arranged beyond the end of said chute, said magnetic flux being adapted to retard checks passing therethrough differentially in accordance with their composition, said chute being adapted to discharge checks in a direction other than vertical, whereby they will travel along trajectories determined by their momentum and gravity, said impact means having an impact face defined by two edges located substantially at the outer limits with in which the trajectories of a certain kind of checks lie, a check receiving passage, and deflecting means adapted to exclude checks rebounding from said impact means from said check receiving passage, except those traversing a certain path. 40 45 50
